UNITED STATES PATENT OFFICE.

TOMASZ HALAGARDA, OF OMAHA, NEBRASKA.

SPRINKLER SYSTEM.

Application filed May 11, 1921. Serial No. 468,665.

To all whom it may concern:

Be it known that I, TOMASZ HALAGARDA, a citizen of Poland, residing at Omaha, in the county of Douglas and State of Nebraska, have invented certain new and useful Improvements in Sprinkler Systems, of which the following is a specification.

This invention relates to what are known as fire sprinkler systems such as are usually employed in stores, factories and other business places.

The primary object of the invention is to provide an improved system of this class in which the water distributing pipes through which the water passes to the sprinklers are normally emptied and water admitted thereto only in case of fire when it is desired that the sprinklers should operate.

The invention consists in the application to the main water supply pipe and water distributing pipes of an improved apparatus whereby the flow of water from the main supply pipe to the water distributing pipe or pipes is normally cut off, but operated in case of fire to admit the water to the water distributing pipe or pipes and the sprinklers connected therewith.

A further object is to provide an improved combined electrical and mechanical apparatus of the class specified, which is simple in construction and operation, and which will be automatically operated to produce the desired result in the case of fire as hereinafter described.

With the above general objects in view and others that will appear as the nature of the invention is better understood, the same consists of the novel form, combination and arrangement of parts hereinafter more fully described, shown in the accompanying drawings and claimed.

In the drawings, wherein like reference characters designate corresponding parts throughout the several views,

Figure 1 is a diagrammatic view of an apparatus embodying my invention;

Figure 2 is a view partly in section and partly in plan of the device shown in Fig. 3 with the cover removed, and

Figure 3 is an enlarged sectional view taken upon line III—III of Fig. 1 through the combined mechanical valve operating motor and electrical release mechanism therefor.

In the drawings, 5 indicates a main water supply pipe of a water sprinkling system of the class under consideration, and 6 denotes a water distributing pipe which is connected with the pipe 5, and which is provided with sprinkling heads or devices 7 of the usual or any preferred construction, and it will be understood that any number of water distributing pipes 6 may be employed, and also any desired number of the sprinkling devices 7.

The sprinkling device 7 may be provided with fusible heads or caps which are melted in the case of fire, and when the heat reaches a predetermined degree, the water is discharged through said sprinkling devices, under the above conditions in the usual manner, and the details of the construction of these sprinkling devices form no part of the present invention, and are therefore, not shown and described.

In the operation of the apparatus, water is supposed to enter the main supply pipe 5 and pass therethrough in the direction of the arrow a, and said pipe is provided at a predetermined point with a valve device 8 comprising the usual valve casing in which is mounted a valve member provided with a stem 9, the valve device being of the needle or gate type wherein an inwardly and outwardly movable closure device is provided, and wherein, when the stem 9 is rotated in one direction, said valve or closure device and stem both move outwardly for permitting passage of the water to the distributing pipe 6.

A suitable board or plate 10 is mounted adjacent the valve 8 and has a casing fastened thereon composed of a bottom member 11 with attaching means 12 and laterally extending marginal flanges 13 onto which telescope a cover 14 for enclosing the mechanism involving a mechanical motor for rotating the valve stem 9 so as to open the valve 8 and an electro-magnet release mechanism for permitting operation of the motor. This encased mechanism involves a suitable motor frame 15 with a coil spring 16 mounted therein, the frame 15 being fixed to the bottom casing member 11 adjacent one end of the latter, and the spring having one end fixed to a stationary post 17 while its other or inner end is attached to a rotatable power shaft 18. A spur gear 19 is fixed upon the shaft 18 and the same meshes

with another spur gear 20 which is fixed upon a further shaft 21 journaled in the frame 15 forwardly of the shaft 18 and substantially in line with the longitudinal axis 5 of the casing. A suitable shaft hanger or bearing bracket 22 is fixed within the frame 15 forwardly of the shaft 21 and a further shaft 23 is journaled therein at right angles to said shaft 21, a bevel gear 24 being fixed 10 upon the inner end of the shaft 23 so as to mesh with a further bevel gear 25 fixed upon the shaft 21. A forked head 26 is suitably fastened upon the outer end of the shaft 23 exteriorly of the casing, and the arms of this 15 head pass loosely through the hand wheel 27 of the valve stem 9 so as to engage the spokes of said wheel. A further shaft 28 is journaled in the frame 15 beside the shaft 18 and the same has a ratchet wheel 29 fastened thereon and also has a spur pinion 30 fastened thereon, said pinion being in mesh with the spur gear 20, and the ratchet wheel 29 being normally engaged by a 20 spring pressed pawl 31 so as to prevent unwinding of the spring 16. It will thus be seen that when the pawl 31 is released from the ratchet wheel 29, the spring 16 will be permitted to unwind for rotating the shaft 23 through the gearing described, thereby 25 opening the valve 8. The shaft 18 may be extended and provided with a squared end as at 32 for engagement by a suitable key 33 when necessary to rewind the spring 16, the squared end 32 being accessible through an 30 opening 34 in the cover 14, and a keeper or clip 35 being preferably provided upon the board 10 for retaining said key in a convenient position when not in use. A suitable valve 36 may be provided in the main water 35 supply pipe 5 between the distributing pipe 6 and the valve 8 so as to permit repairs upon the sprinkler head and the like when said valve 36 is closed and without disturbing the valve 8.

40 An electro-magnet 37 is rigidly mounted within the casing so as to attract a pivoted armature 38 which has a contact 39 fastened upon one end thereof normally out of engagement with a stationary contact 40 fixed to the bottom member 11 of the casing. The armature 38 is normally held away from the core of the spools of the electro-magnet by means of a spring 41, and upon attraction of said armature, the contact 39 moves into engagement with the contact 40. A bifurcated plate 42 is fastened to the armature 38 so as to extend toward the ratchet wheel 29, and one arm of the plate 42 is formed as at 43 to engage an upstanding pin 44 on the pawl 31 so as to disengage said pawl from the ratchet wheel when the armature 38 is attracted. The other arm of the plate 42 is extended as at 45 beside the shaft 28 where it is connected by means of a rod 46 to a 45 coil spring 47 which has one end attached

to a post 48 and which loosely encircles the shaft 28. The spring 47 merely provides additional means for releasing the arm 43 from the pawl 31 and for outwardly swinging the armature 38 to the position shown in Fig. 2 wherein contacts 39 and 40 are separated.

70 A wire 49 extends from the movable contact 39 to one spool of the electro-magnet as at 50, and another wire 51 extends from the point 50 to one side of a suitable battery 52. A further wire 53 extends from the stationary contact 40 to a suitable alarm 54 which may be located at fire headquarters, and a return wire 55 extends from the other side of the alarm 54 to the battery 52. A still further wire 56 extends from the other spool of the electro-magnet where it is connected in parallel by means of wire generally denoted by the numeral 57 with a plurality of thermostatic switches 58, one of which is located adjacent each of the sprinkler heads 7, and the other sides of which thermostatic switches are connected as at 59 with the battery 52. It is to be understood that the thermostatic switches 58 may be of any well known or preferred construction wherein the movable contact is normally out of engagement with the stationary contact and which movable contact is automatically actuated through excessive heat to engage the stationary contact.

75 The operation will be readily understood from the foregoing description when taken in connection with the accompanying drawing and the following statement.

80 Under normal conditions, the main water supply pipe 5 at the inlet side of the valve 8 will be filled with water while the remainder of said pipe and the distributing pipe or pipes 6 will be emptied. If, under these conditions, a fire should originate in a place provided with my improved apparatus, and the temperature should rise to a point or degree at which the heads of the sprinkling device 7 will be fused, the thermostatic switches 58 will also be actuated by the heat so that the movable contacts thereof engage the fixed contacts of the same. Upon closing of the thermostatic switches 58 of any one of the same, the current is permitted to flow through the spools of the electromagnet 37 by way of wires 59, 57, 56 and 51 and this causes attraction of the armature 38 so as to swing the contact 39 into engagement with the contact 40, and this closes a circuit from the battery through wire 55, alarm 54 and wires 53 and 51 back to the battery so that an alarm is given at fire headquarters. At 85 the same time that the armature 38 is swung by traction as above outlined, the arm 43 of the plate member 42 disengages the pawl 31 from the ratchet wheel 29 and the spring 16 is thus allowed to rotate the forked head 26 for opening the valve 8. The flow of 90

- water through the sprinkler heads will continue until the thermostatic switches 58 are automatically returned to open position and the valve 8 is returned to its normal closed 5 position, or the water may be cut off by hand manipulation of the valve 36. A spanner wrench 60 may be held by a suitable clasp or keeper 61 on the board 10 for convenient operation of the valve 36.
- 10 With my apparatus it will be seen that there will be no water in the distributing pipe or pipes 6 nor sprinkling devices 7, and this, as is evident, will prevent the freezing and bursting of such devices in extremely 15 cold water and thus will prevent great loss and damage as will be readily understood.
- It also sometimes happens when sprinkling apparatus of the kind herein described is employed, that the heads of the sprinkling 20 devices are accidentally broken off and this, of course, would also result in great loss and inconvenience if the distributing pipes were full of water, all of which loss and inconvenience is obviated by my improvements.
- 25 From the foregoing description, it is believed that the construction and operation as well as the advantages of the present invention will be readily understood and appreciated by those skilled in the art.
- 30 What is claimed as new is:—
1. In a valve operating mechanism, a valve, a wheel secured to the stem of said valve, a shaft supported in axial alinement with said stem, a forked head carried by 35 said shaft operatively engaging the spokes of said wheel, a pair of gear carrying shafts positioned to extend at right angles to the first mentioned shaft, a spring motor mounted upon one of the last two mentioned shafts, 40 means for connecting the first mentioned shaft with the pair of right-angularly arranged shafts, means for normally retaining the spring motor inoperative, electrical means for releasing said motor, a normally 45 open circuit for the electrical means, and means for closing said circuit when the operation of said valve is desired.
  2. In a valve operating mechanism, a valve having a stem, a shaft supported in 50 axial alinement with said stem, means for connecting said shaft and stem so that rotation of the former will rotate the latter, a pair of gear carrying shafts positioned to extend at right angles to the last mentioned 55 shaft, a spring motor mounted upon one of the last mentioned shafts, means for connecting the first mentioned shaft with the pair of right-angularly arranged shafts, means for normally retaining the spring 60 motor inoperative, electric means for releasing said motor, a normally open circuit for the electric means, and means for closing said circuit when the operation of said valve is desired.
  3. In a valve operating mechanism, a 65 valve having a stem, a shaft supported in axial alinement with said stem, means for connecting said shaft and stem so that rotation of the former will rotate the latter, a pair of gear carrying shafts positioned to extend at right angles to the last mentioned shaft, a spring motor mounted upon one of the pair of gear carrying shafts, a gear connection between the last mentioned shaft and the pair of right-angularly arranged shafts, a pawl and 70
- valve having a stem, a shaft supported in axial alinement with said stem, means for connecting said shaft and stem so that rotation of the former will rotate the latter, a pair of gear carrying shafts positioned to 75 extend at right angles to the last mentioned shaft, means for connecting the first mentioned shaft with the pair of gear carrying shafts, mechanical means for rotating one of said last mentioned shafts, means for normally retaining the mechanical means inoperative, electric means for releasing said last mentioned means, a normally open circuit for the electric means, and means for closing said circuit when the operation of said valve is desired.
4. In a valve operating mechanism, a valve, a wheel secured to the stem of said valve, a shaft supported in axial alinement with said stem, a forked head carried by 80 said shaft operatively engaging the spokes of said wheel, a pair of gear carrying shafts positioned to extend at right angles to the last mentioned shaft and having a portion of their gears connecting said pair of shafts, 85 mechanical means for rotating one of said last mentioned shafts, a gear connection between the first mentioned shaft and the pair of right-angularly arranged shafts, means for normally retaining the mechanical 90 means inoperative, electrical means for releasing said last mentioned means, a normally open circuit for the electric means, and means for closing said circuit when the operation of said valve is desired.
5. In a valve operating mechanism, a valve, a wheel secured to the stem of said valve, a shaft supported in axial alinement with said stem, a forked head carried by 95 said shaft operatively engaging the spokes of said wheel, a pair of gear carrying shafts positioned to extend at right angles to the last mentioned shaft, a spring motor mounted upon one of the last mentioned shafts, means for connecting the first mentioned 100 shaft with the pair of right-angularly arranged shafts, a pawl and ratchet mechanism for normally retaining the spring motor inoperative, electric means for operating said pawl to release said ratchet wheel, a normally open circuit for the electric means, and means for closing said circuit when the operation of said valve is desired.
6. In a valve operating mechanism, a valve, a wheel secured to the stem of said valve, a shaft supported in axial alinement with said stem, a forked head carried by 105 said shaft operatively engaging the spokes of said wheel, a pair of gear carrying shafts positioned to extend at right angles to the last mentioned shaft, a spring motor mounted upon one of the pair of gear carrying shafts, a gear connection between the last mentioned shaft and the pair of right-angularly arranged shafts, a pawl and 110
- 115
- 120
- 125
- 130

ratchet wheel mechanism for normally retaining the spring motor inoperative, electro-magnets for operating said pawl to release said ratchet wheel, a normally open circuit for the electro-magnets, and means for closing said circuit when the operation of said valve is desired.

In testimony whereof I affix my signature in presence of two witnesses.

TOMASZ HALAGARDA.
